J. M. ANGELETTI

ILLUMINATING TIMEPIECE

Filed Sept. 6, 1922

INVENTOR

Joseph M. Angeletti

BY

W. J. Criswell
ATTORNEY

UNITED STATES PATENT OFFICE.

JOSEPH M. ANGELETTI, OF NEW YORK, N. Y.

ILLUMINATING TIMEPIECE.

Application filed September 6, 1922. Serial No. 586,453.

To all whom it may concern:

Be it known that I, JOSEPH M. ANGELETTI, a subject of the King of Italy, and a resident of New York, in the county of New York and State of New York, have invented certain new and useful Improvements in Illuminating Timepieces, of which the following is a full, clear, and exact specification.

10 This invention relates more particularly to a class of registering devices.

15 My invention has for its object primarily to provide a timepiece or registering device designed to be employed for permitting the time of a day to be observed when the holder of the device is in a lighted or dark place by reason of the device being preferably of a form adapted to be illuminated, and which is also of a type wherein the use 20 of hands for indicating the time are dispensed with. The invention consists mainly of the provision of indicators preferably in the forms of rotary disks having indicia used in conjunction with the operating 25 mechanism of a timepiece whereby the time in hours, minutes and seconds may be indicated instead of using the customary hand elements for indicating the time. I also may employ in association with the operating 30 mechanism a lamp which is lighted by the circuit from a battery carried in proximity to the mechanism.

35 A further object of the invention is to provide an illuminating timepiece of a simple, efficient and durable construction which may be made in any appropriate shape and size.

With these and other objects in view, the invention will be hereinafter more fully described with reference to the accompanying drawing forming a part of this specification in which similar characters of reference indicate corresponding parts in all the views, and will then be pointed out in the 45 claims at the end of the description.

In the drawing, Figure 1 is a front elevation of one form of illuminating timepiece embodying my invention.

Fig. 2 is an enlarged detail sectional view, 50 partly fragmentary and partly broken away, taken through the timepiece with its front plate swung to an open position.

Fig. 3 is a detail sectional view taken on the line 3—3 of Fig. 2, and

Fig. 4 is a fragmentary view, partly in detail, taken on the line 4—4 of Fig. 2.

The device or timepiece has a casing 10 which may be of any appropriate shape and size, though in the drawing I have illustrated a watch as the preferred form for carrying into practice the invention. The casing 10 has an annular frame 11 with a front plate 12 which may be removable or hinged to the frame, and on the rear of the casing is a plate 13 which may be removable, or stationary or hinged also to the frame for being swung to open and closed positions, in order to obtain access into the interior of the casing. Protruding from part of the periphery of the frame 11 in a tubular post or sleeve 14 having its passageway leading through an opening in the frame into the interior of the casing, and in the central part of the front plate 12 is an exposure window 15 of glass or other transparent material. As shown, this observation window is circular as well as being of a suitable diameter. Cut or otherwise inscribed on the window 15 is provided a character or suitable indicia, as 16, which may be in the form of a line or arrow to indicate the time.

Revolvable crosswise of the window 15 relative to the indicia 16 are two indicators or dials 17 and 18 which are preferably in the forms of circular superimposed disks. The disk or dial 17 is of considerably larger diameter than the disk 18, and on the marginal part of the exposed face of the disk 17 is an annular scale divided into twelve equal sections, each being numbered, as at 19, or otherwise designated by a distinctive character for serving as indicia whereby the hours of a day may be indicated. Also on the marginal part of the exposed face of the disk 18 is another annular scale divided into sixty equal sections, each being preferably numbered, as at 20, for serving as indicia whereby the minutes of each hour of the day may be indicated. These hour and minute indicating disks are arranged interiorly of the casing so that desired portions of their time indicating indicia 19 and 20 will be exposed to view through the window 15 of the casing when revolved similar to the revolving of the usual hour and minute hands of a watch or clock. Like the mounting of the hands of a watch or clock these time indi-

cating disks are also mounted on the main pivot element, as 21, of the operating mechanism, as 22, of the timepiece so that they will be relatively revolved with relation to the indicia 16 when the mechanism 22 is operated for indicating the time, as will be hereinafter more fully explained.

The mechanism 22 may include constructive parts of forms commonly used in watches, excepting that the parts of the mechanism shown are of sizes and so arranged that they occupy approximately one-half the interior of the casing 10 with the gear, as 23, which carries the main spring 24 being in proximity to the sleeve 14 of the frame 11 of the casing and so that the pivot element 21 will revolve the disks 17 and 18 crosswise of the window 15. The spring 24 is tensioned for operating the mechanism by the manual operation of a stem winding and setting device or key, as 25. This winding device may be of a well known type, such as a form composed of a stem 26 which is revolvably and slidably disposed in the sleeve 14 of the frame 11 of the casing, and the stem is of a length so that its lower end protrudes into the casing, while its upper end extends above the sleeve. On the upper end of the stem 26 is a head or cap 27 which is of a size as well as being arranged so that it movably fits over the upper end of the sleeve 14, and in the upper end of the sleeve may be an annular socket, as 28, surrounding the passageway of the sleeve. In the socket 28 and encircling the stem is a spiral spring 29 which presses against the under side of the cap 27 and also presses upon the bottom of the socket 28, and this spring is tensioned for serving to normally force the cap upwardly as well as forcing the stem 26 outwardly of the casing and of the sleeve 14. On the lower end of the stem 26 is a gear 30 which meshes with the gear 23 for operating the spring 24 of the mechanism to operate the time indicating disks 17 and 18 by accordingly revolving the cap 27 and the stem 26 of the winding device. Associated with the disks 17 and 18 is a train of gears, as 31, Fig. 4, and one of these gears, as 32, is in mesh with a gear, as 33, having in its center a square socket, not shown, for removably receiving the square portion, as 34, provided on the lower end of the stem 26 of the winding device so that the disks 17 and 18 may be set at desired intervals for keeping time by pressing the cap 27 against the tension of the spring 29 to force the stem inwardly of the casing so that the square end portion 34 of the stem will be removably seated in the square hole of the gear 33. By then rotating the cap 27 and stem 26 accordingly the train of gears 31 will be operated to properly set the time indicating disks 17 and 18. In order that

the seconds of a minute may be indicated, on a pivot, as 35, which is rotatable by the mechanism 22 relative to the rotation of the disks 17 and 18 is another circular disk, as 36, and on the marginal edge portion of the disk 36 is indicia 37 in the forms of equidistant spaced numerals for indicating in succession each five seconds of a minute, and on the window 15 of the casing may be indicia, as 38, in the form of a line or arrow with which the indicia 37 is registrable for indicating the seconds of a minute relative to the time indicated by the hour and minute disks 17 and 18.

Serving to enable the time of the day to be observed in dark places within the casing 10 under the window 15 is a lamp, as 39, and this lamp is preferably of a class adapted to be lighted by electricity through the medium of the circuit, as 40, of a battery 41 of a suitable dry cell type, though the battery shown is of a well known make having a carbon core 42 serving as one of its terminals and having a conductive shell or casing, as 43, serving as its other terminal. The battery 41 is of an approximately semi-circular shape of a size so that it is removably arranged in the second half of the interior of the casing 10. Fastened, at 44, to the carbon or terminal 42 of the battery 41 is a conductive clamp or clip, as 45, of spring metal of substantially a U-shape to provide two spaced yielding prongs, as 46, 47, and the outer end portions of these prongs are oppositely curved for receiving and releasably gripping the socket or one pole, as 48, of the lamp 39. The second pole, as 49, of the lamp abuts against a contact or conductive wire, as 50, which is insulated, as at 51, from the casing 10, and this wire leads to a bracket, as 52, which may be of substantially the shape of an inverted L. One of the arms of the L-shaped bracket is also insulated, as at 53, from the casing, and protruding upwardly from the second arm of the bracket is a conductive post or contact 54 which terminates at the square hole of the gear 33 so that the stem 26 of the winding and setting device 25 will contact therewith when the stem is pressed inwardly of the casing and through the opening of the gear 33. On the inner face of the frame 11 of the casing 10 is held one end of a contact or conductive wire, as 55, having its other end in contact with the shell 43 of the battery 41. The circuit 40 formed by these parts is closed for lighting the lamp 39 at intervals by pressing the head 27 and stem 26 inwardly of the casing against the tension of the spring 29. The square end 34 of the stem will then pass through the hole in the gear 33 for contacting with the post 54 of the bracket 52, and the circuit will then be closed from the carbon terminal to the con-

ductive prongs 46, 47 to one pole of the lamp 39. From the conductive shell 43 of the battery the circuit will be closed over the wire 55, through the frame 11 of the 5 casing, through the stem 26 of the winding device 25, over the post 54, over the bracket 52 and through the wire 50 to the second pole of the lamp which will be lighted to illuminate the window 15, and the indicia of 10 the disks 17, 18, 36 to enable the time of the day to be observed especially in dark places.

In the foregoing description, I have embodied the preferred form of my invention, but I do not wish to be understood as 15 limiting myself thereto, as I am aware that modifications may be made therein without departing from the principle or sacrificing any of the advantages of this invention, therefore, I reserve to myself the right to 20 make such changes as fairly fall within the scope thereof.

Having thus described my invention, I claim as new and desire to secure by Letters Patent:

25 1. The combination with the operative mechanism of a stem winding timepiece having a conductive casing with a battery and a lamp therein, and the casing having a window, of two superposed disks relative-
30 ly revolvable with the operation of the mechanism crosswise of the window, one disk having characters for indicating the time by hours and the other disk having char-

acters for indicating the time by minutes, a third disk relatively rotatable with the operation of the mechanism also crosswise of the window and having characters for indicating the time by seconds, a conductive slip supporting the lamp and leading from one of its poles to one terminal of the battery, 35 conductors leading from the second terminal of the battery to the casing, a conductive substantially L-shaped bracket leading from the second pole of the lamp, and a conductive post on the bracket for 40 engagement with operation of the stem winder of the mechanism to close the circuit over the post and over the bracket to 45 the battery.

2. The combination with the operative 50 mechanism of a stem winding timepiece having a conductive casing, of a battery in the casing, a lamp in the casing, a conductive clip on one terminal of the battery, and engaging the conductive shell forming one 55 pole of the lamp, conductive means leading from the second pole of the battery to the casing, and conductive connections leading from the second pole of the lamp for engagement with the operation of the stem 60 winder to close the circuit for lighting the lamp.

This specification signed and witnessed this 5th day of September A. D. 1922.

JOSEPH M. ANGELETTI.
